UNITED STATES PATENT OFFICE.

HYMEN ZIMMERMAN, OF NEW YORK, N. Y., ASSIGNOR TO ART CAGE MANUFACTURING COMPANY, INC., OF NEW YORK, N. Y., A CORPORATION OF NEW YORK.

DESIGN FOR A CAGE BOTTOM OR SIMILAR ARTICLE.

Application filed November 5, 1925. Serial No. 15,358. Term of patent 14 years.

To all whom it may concern:

Be it known that I, HYMEN ZIMMERMAN, a citizen of the United States, residing at the city of New York, county and State of New York, have invented a new, original, and ornamental Design for Cage Bottom or Similar Article, of which the following is a specification, reference being had to the accompanying drawing, forming part thereof.

Fig. 1 is a plan view of a cage bottom or similar article showing my new design.

Fig. 2 is a front view of the same, and

Fig. 3 is a perspective view of the same.

I claim:

The ornamental design for a cage bottom or similar article as shown.

HYMEN ZIMMERMAN.
